DRESS FORM

Jessie S. Stoddard, Fairfield, Conn.

Application April 3, 1956, Serial No. 575,853

4 Claims. (Cl. 223—68)

The present invention relates to a dress form, particularly for support upon a suitable dress form stand, and has for an object to provide a dress form which simulates the upper torso, particularly the shoulders, chest, waist and hips.

It is particularly proposed to provide a dress form which is flexible and at the same time has a substantially solid body structure, so that with proper interior support it will provide a form which may be made to conform to a particular desired shape, and at the same time will be sufficiently firm to maintain such shape under fitting and dress making conditions.

To this end it is proposed to provide a dress form constructed of an outer flexible layer, preferably of woven fabric, and which is made to a pattern sized to the particular shape of the person whose form is being simulated, and an inner liner consisting of relatively thick foam rubber sheeting cut to a pattern corresponding to the pattern of the outer layer and having its edges butted and suitably secured, so that the inner lining presents a substantially smooth even thickness reinforcement for the outer layer.

It is further proposed to provide stiffening means at the lower edge of the hip section, at the waist, around the neck opening, and around the arm holes, consisting of wire loops of soft, bendable wire, whereby these areas may be readily conformed to desired shapes.

A further object is to provide a dress form which may be readily engaged or disengaged upon the supporting stand, and to this end it is proposed to provide closure means extending the full length of the back.

A further object is to provide a dress form which when not in use may be compactly folded for convenient storage.

It is a still further object of the invention to provide an adjustable hip-shape insert adapted for interposition between the hip portion of the flexible dress form and the supporting stand, the latter preferably of the truncated cone type as disclosed in my co-pending application for Dress Form, Serial Number 549,287 filed November 28, 1955.

Other objects and advantages of the invention will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

Fig. 1 is a front elevation of the dress form of the invention;

Fig. 2 is a side elevation;

Fig. 3 is a vertical sectional view taken along the line 3—3 of Fig. 1;

Fig. 4 is a view partially in rear elevation and par-

2

tially in vertical section, taken along the line 4—4 of Fig. 2;

Fig. 5 is an enlarged detail sectional view taken along the line 5—5 of Fig. 4;

Fig. 6 is an enlarged detail sectional view taken along the line 6—6 of Fig. 4;

Fig. 7 is an enlarged detail sectional view taken along the line 7—7 of Fig. 4;

Fig. 8 is an enlarged detail sectional view taken along the line 8—8 of Fig. 4;

Fig. 9 is a perspective view of a type of supporting form upon which the shoulder and chest portion of the dress form of the invention is adapted to be supported, the particular supporting form illustrated being of the type disclosed in my co-pending patent application for Dress Form, Serial Number 563,004 filed February 2, 1956;

Fig. 10 is a perspective view of an accessory hip-shape insert adapted for use with the dress form of the invention; and

Fig. 11 is a front elevation showing the dress form as supported upon a stand of the type as illustrated in my co-pending patent application for Dress Form, Serial Number 549,287 filed November 28, 1955, and in which the supporting form as shown in Fig. 9 and the accessory hip-shape insert as shown in Fig. 10 are incorporated.

Referring to the drawings, the dress form, according to the illustrated exemplary embodiment of the invention, comprises generally an outer layer 10 preferably of woven fabric material, and an inner layer 11 of relatively thick, for example one-half inch, foam rubber sheet material, upon one face of which there is laminated a woven fabric backing 12 which, in addition to giving added body and strength to the foam rubber, provides means which will receive securing stitching so that the latter will be firmly held with respect to the foam rubber and will not tend to tear the edges of the foam rubber.

The outer layer 10 is cut to a pattern similar to that employed in dress making, and which may be furnished in an approximate size so that the person using the pattern may adapt the size to particular measurements, for example, in the case of a waist measurement or a dart cutout, these may be altered according to well-known dress making practice to fit the particular person for whom the form is being made.

The outer layer 10 comprises an upper front section 13 having dart cutouts secured along the seam lines 14 to give the desired bust contour to the front section, a lower front section 15 having dart cutouts secured along the seam lines 16, an upper back section comprising right and left parts 17—17 having dart cutouts secured along the seam lines 18, and a lower back section comprising right and left parts 19—19 having dart cutouts secured along the seam lines 20.

The upper front and back sections 13 and 17 are secured to the lower front and back sections 15 and 19 at the waist line along the seam line 21, the side edges of the upper front and back sections are secured along the seam lines 22, the lower front and back sections are secured along the seam lines 23, and the upper edges of the shoulder portions of the front and back sections are secured along the seam lines 24. The front and back sections are provided at each side with armhole cutouts 25 and 26 which together provide armhole openings, and the upper edges of the upper front and back sections are provided with neck cutouts 27 and 28 which together provide a neck opening. The several seams employed in the outer layer 10 are of the usual plain or flat machine stitched type.

The foam rubber inner layer 11 consists of a plurality of pieces of foam rubber sheeting corresponding to the

plurality of pieces making up the sections of the outer layer, and each having dart cutouts corresponding to the dart cutouts of the outer layer. The edges of the dart cutouts and the adjoining edges of the several sections of the inner layer are butted and suitably secured, preferably by criss-cross hand stitching 29. The inner layer is secured in place by a woven fabric neck-band portion 30 secured to the marginal edge portion of the neck opening of the outer layer along a seam line 31, the neck-band portion being folded in upon the inner side of the upper neck opening portion of the inner layer and secured by criss-cross hand stitching 32 caught into the fabric backing 12 of the inner layer. Within the fold of the neckband portion 20 and positioned against the upper edge of the inner layer is a stiffening wire loop 33.

A woven fabric armhole band portion 34 is secured along a seam line 35 to the marginal edge portion of each armhole opening, and is folded in upon the inner side of the inner layer and secured by criss-cross hand stitching 36 caught into the fabric backing 12 of the inner lining. A stiffening wire loop 37 is positioned within the fold of the band portion 34 against the edge of the armhole opening of the inner layer. At the waistband a stiffening wire loop 38 is interposed between the opposed edges of the upper and lower sections of the inner layer, being retained in place against the seam 21 by the criss-cross hand stitching 29 connecting the upper and lower sections of the inner layer and caught into the fabric backing 12. The bottom edge of the inner layer is secured by an inwardly and upwardly turned hem portion 39 of the outer layer having its edge secured to the inner layer by criss-cross hand stitching 40 caught into the fabric backing 12. A stiffening wire loop 41 is disposed in the fold of the hem against the lower edge of the inner layer.

The meeting edges of the right and left parts of the back section are adapted to be secured by a zipper fastener of the usual type consisting of a pair of tapes 42 and 43 having interlocking tooth formations 44 and 45 secured thereto, a slide 46 (Fig. 4) being operable to close or open the fastener. As shown clearly in Fig. 8, the marginal edges of the back sections are folded in, as at 47, and are secured by lines of stitching 48 and 49 to the two tape members 42 and 43 of the zipper fastener. These tapes are in turn secured by tacking stitches 50 and 51 to the fabric backing 12 of the inner layer 11, so that the meeting edges of the back sections of the inner layer are thus secured relatively to the meeting edges of the right and left parts of the outer layer.

The stiffening wires 37 in the case of the armholes, are preferably a continuous loop, i. e., the ends of the wires may be slidably overlapped for adjusting the size of the loop or they may be of a fixed size by soldering or otherwise securing the ends together. In the case of the neck, waist and hemline wires, these have their ends terminating adjacent the meeting edges of the right and left parts of the back sections and, as shown in Fig. 8 with reference to the hemline, each of these wires has its terminal ends curled as at 52 to eliminate sharp ends, as well as to hold the wires against shifting. The stiffening wires are preferably formed of a soft wire which may be readily bent to shape and which will retain the shape to which it is bent, so that the neck opening, armholes, waist and hem line may be shaped by the wires to desired forms at these areas of the dress form.

The dress form, according to the invention, provides a structure which is self-sustaining with a minimum amount of interior support, so that if desired it may be used without employing a supporting stand, simply by placing paper or other suitable substance within the form to maintain it against inward distortion while it is being used. However, it is preferred to support the dress form upon a suitable dress form support. A suitable support for this purpose is the dress form as disclosed in my co-

pending application Serial Number 549,287 which, as shown in Fig. 11, consists of a truncated cone-shaped body 53 supported upon a vertically adjustable tripod stand 54 and having laterally projecting shoulder support arms 55 supported upon a vertically adjustable center rod 56 extending upwardly from the upper end of the body 53.

Upon the shoulder support arms 55 there may be engaged a dress form support simulating the shape of the shoulder and chest, and this form is preferably of the type as disclosed in my copending application Serial Number 563,004. This consists generally of a plurality of flexible fiberboard members 57 which have overlapping edges adjustably secured together by fasteners 58. The support 57 is engaged upon the shoulder support 55 which is 15 adjusted vertically at the proper distance above a given waist line point upon the cone body 53, and the cone body may be adjusted by the tripod stand so that the waist line point is at a desired distance from the floor. The form 57 has front and rear downwardly projecting 20 strip members 59 and 60 which are adapted to fit against the cone member 53 within the waistband portion of the dress form supported thereon.

The dress form of the invention is fitted upon the support as shown clearly in Fig. 11, and in order to fill 25 out the hip portion and to give the desired outline shape thereto, a hip-shape insert, as shown in Fig. 10, is preferably engaged upon the cone body 53 and is fitted within the lower portion of the dress form. This consists of a truncated cone-shaped band 61 which has overlapping 30 edges provided with perforations 62, by means of which the overlapped edges may be secured as desired by suitable fasteners 63 to provide a desired circumference. This band is adapted to be firmly engaged upon the truncated cone member 53. Secured to the band 61 are 35 a pair of flexible fibreboard members 64 and 65 having overlapped edges provided with perforations 66 and which are adapted to be secured in adjusted relation to each other and to the band 61 by fasteners 67, so that the members 64 and 65 may loop out from the band to 40 any desired extent. In order to give the desired hip curvature to the members 64 and 65, dart cutouts 68 are provided, the edges of which are overlapped and secured at adjusted positions by fasteners 69.

A similar rib insert may be provided above the waist 45 by inverting the position of the members 64 and 65 upon the band 61, the members 64 and 65 being secured upon the band 61 so that their lower edges are substantially at the waist line point, this point preferably being adjacent the lower end of the band 61, instead of 50 adjacent the upper edge as shown in Figs. 10 and 11. By having the waist line point substantially midway between the upper and lower edges of the band, members 64 and 65 may be secured below the waist line to simulate 55 a hip form and members 64 and 65 may be secured in inverted relation above the waist line to simulate a rib form.

What is claimed is:

1. A hollow dress contour form comprising a wall having a neck opening in the upper end, arm hole openings at opposed sides and an open lower end, said wall consisting of an outer layer comprising pieces of woven fabric material, at least some of said pieces having dart cuts, stitched seams securing the edges of said dart cuts and adjacent edges of said pieces of material to give non-flat contours to said wall, and an inner layer formed of pieces of normally flat relatively thick sponge rubber sheet material of uniform thickness throughout in substantial register with and of substantially corresponding outline shape to said pieces of said outer layer and having dart cuts substantially corresponding to and in substantial register with said dart cuts thereof, adjacent edges of said pieces of sheet material butting each other, stitching securing said butted edges together independently of the stitched seams of said outer layer, band portions of woven fabric material connected to said

edges of the neck opening, said arm openings, and said lower open end, said band portions each having an in-folded portion engaged upon said inner layer, stitching securing said in-fold band portions to said inner layer, and stiffening wires respectively extending about said neck opening, said arm openings and said open lower end, said wires being respectively disposed within said in-fold band portions and butting against the edges of said inner layer extending about said neck opening, said arm openings and said open lower end.

2. The invention as defined in claim 1, further characterized in that said inner layer includes a reinforcing adhered lamination layer of woven fabric material one side of said sheet material and disposed adjacent said outer layer, said stitching securing the butted edges of said pieces of said inner layer also engaging and securing said reinforcing layer.

3. The invention as defined in claim 1, wherein said form is provided with a vertical split extending between said neck opening and said open lower end, and a zipper 20 fastener for opening and closing said split, said zipper

fastener including a pair of tapes, stitched seams securing said tapes to said outer layer at opposite sides of said split, and stitching securing said tape to said inner layer at opposite sides of said split.

4. The invention as defined in claim 1, wherein said form includes a contracted waist portion defined by a stitched seam securing upper and lower pieces of said outer layer, and stitching securing upper and lower pieces of said inner layer, and a stiffening wire extending about said waist portion inwardly of said outer layer and disposed between the butted edges of said upper and lower pieces of said inner layer.
